UNITED STATES PATENT OFFICE.

CHARLES LOUIS ROSZAK, OF PARIS, FRANCE, ASSIGNOR TO THE BABCOCK & WILCOX COMPANY, OF NEW YORK, N. Y.

WATER-TUBE BOILER.

Application filed July 21, 1927, Serial No. 207,517, and in France July 19, 1926.

The present invention relates to a water-tube boiler of the substantially vertical tube type fired with fuels such as pulverized coal, gases or liquids.

5 In existing boilers of this type, and particularly boilers fired with pulverized fuel, the flame passes into a huge combustion chamber of parallelepiped form and immediately expands, thus considerably diminishing the speed of flow of the gases. As 10 the rate of heat transference falls with the fall in speed of the heating medium, it is an advantage to have a combustion chamber shaped to conform with the flame so as to 15 maintain the speed of flow of the gases.

The present invention provides an improved form of combustion chamber the walls of which are formed by water tubes disposed to limit the expansion of the combustion gases, while preserving their direction and speed, the flame having a vertical axis and being directed upwardly whether there is a single jet or row of jets or a pair of convergent jets or rows of jets.

25 The advantages of this arrangement may be summarized as follows:

The zone of maximum temperature is disposed towards the upper ends of the tubes;

The generation of steam will take place 30 mainly towards the upper ends of the tubes, in the region of maximum temperature. The distance through which the bubbles of steam will flow from their starting point to the water level in the upper drum will be 35 very short and consequently the steam passing into the said drum will be particularly dry; since there are rows of tubes on opposite sides of the flame issuing from the burners substantially the entire heat radiated by the flame will be absorbed by the direct surface.

The ash-containing dust which may fuse in the flame will be solidified by the cold walls and will again become pulverulent in 45 the gases and will not agglomerate; the direct heating surface of the boiler will thus act as a water-screen;

The combustion chamber being of rational shape, since it takes the form of the flame, 50 does not require to be abnormally high;

The return flow of the gases downwardly towards the flue or flues ensures the deposit of the ashes in two large ash chambers situated at the lower end of the boiler, whence

they may be removed by suitable appliances; 55

The accumulation of soot will be avoided, as the lower drums are free at both sides and the tubes are nearly vertical;

It is to be noted that the fuel-laden air jet issuing from the burner is delivered at a 60 high speed sufficient for the suspension of the particles of coal in the air. This speed is sufficient to ensure that the flame will reach the upper end of the boiler.

The invention will be understood from 65 the description in connection with the accompanying drawings. In the drawings Figs. 1, 2, 3 and 4 are vertical sections through illustrative embodiments of the invention, partly diagrammatic; Fig. 5 is a 70 diagrammatic end view showing the general arrangement of an illustrative embodiment of the invention; and Fig. 6 is a side view corresponding to Fig. 5.

The same reference characters indicate 75 like parts in the different figures of the drawings.

In the drawings, reference character R indicates an upper steam and water drum that is connected to lower water drums *r* and *r'* by banks of vertically disposed tubes *T* and *T'*. The tubes *T* and *T'* are so shaped and spaced that they bound a combustion chamber having in cross section a generally pear-shaped outline that conforms to the outline 85 of a free flame passing vertically upwards from a row of fuel burners *B*. The space between the inner rows of tubes of each bank of tubes *T* and *T'* is divided into an upper chamber *D* and a lower chamber *D'* connected by a restricted passage *E* as most clearly shown in Figs. 2 and 3. The fuel burners *B* are located in the lower chamber *D'*. Substantially vertical baffles *C* and *C'* are located on opposite sides of the pear-shaped combustion chamber and may be so 95 located that a portion of each bank of tubes is on opposite sides of the baffles as indicated in Figs. 1, 2 and 3, or the baffles *C* and *C'* may be so located that all of the tubes *T* and *T'* are outside of the same as indicated in Figs. 4 and 5. The flame and gases entering through the burners *B* pass upwardly as indicated by the arrows, thence

over the top edges of the baffles *C* and *C'* and downwardly between these baffles and the outer walls of the boiler and through openings *o* and *o'* into an outlet flue *P*. 100

Openings o and o' may also be provided in the lower portions of the outer walls of the boiler to permit waste gases to pass therethrough. Downcomer tubes represented by the dotted lines p and p' in Figs. 1, 2 and 5, and by solid lines in Figs. 3 and 6, may be located outside of the boiler walls and connect the upper drum R to the lower drums r and r' . Ash pits d and d' are located on opposite sides at the bottom, in which ash pits dust soot or ashes may collect and be removed in the usual way.

In the modification shown in Fig. 2, the products of combustion after passing downwardly on the outside of the baffles C and C' , then pass upwardly through flues in which economizers E and E' are located, these flues extending upwardly between the combustion chamber and the outer walls of the boiler. In this modification, superheaters S and S' are shown in the space above the baffles C and C' and air heaters A and A' are shown below the drums r and r' composed of tubes lying along the inside wall 25 of the ash pits d and d' .

In the modification shown in Fig. 3, the openings o and o' for the products of combustion are disposed in a manner similar to that shown in Fig. 1, and the superheaters E and E' are located in the lower portion of the boiler setting so that the products of combustion pass over the superheater tubes just before they enter the outlets o and o' .

The modification shown in Fig. 4 is somewhat similar to that shown in Fig. 2, but in this modification the baffles C and C' lie entirely within the bank of tubes T and T' .

In the diagrammatic illustration of Fig. 5, the path of the products of combustion is

indicated by the arrows all the way to the stack in an embodiment in which the economizers are located in flues on opposite sides of the boiler; and Fig. 6 is a side view in which the arrangement of the row of burners B is more clearly indicated in dotted lines.

The tunnel X from which the burners project may serve for housing the necessary apparatus and motors, thus saving boiler space.

I claim:—

1. In a water tube boiler, an upper drum, a plurality of spaced lower drums, banks of tubes connecting said upper drum to said lower drums, and forming a combustion space therebetween, the innermost row of tubes on opposite sides of said combustion space having the lower portion bent towards each other to a distance less than the distance between said lower drums to form a constricted passage, and an upper portion bent away from each other, and a burner located below the point where said tubes approach each other nearest.

2. In a water tube boiler, an upper drum, a plurality of spaced lower drums, banks of tubes connecting said upper drum to said lower drums, the inner row of tubes of each of said banks being bent inwardly at their upper ends and at an intermediate point to form in conjunction with said drums, chambers that are connected by a narrow passage, the upper chamber decreasing in size at both ends thereof, and means to cause hot products of combustion to pass downwardly along the outer tubes of said banks.

In testimony whereof I have signed my name to this specification.

CHARLES LOUIS ROSZAK.
